CLAIM

The ornamental design for a display screen with graphical user interface of an incubator, as shown and described.

DESCRIPTION

FIG. 1 is a front view of a first embodiment of a display screen with graphical user interface of an incubator.

FIG. 2 is a front view of a second embodiment of the display screen with graphical user interface of an incubator.

FIG. 3 is a front view of a third embodiment of the display screen with graphical user interface of an incubator.

FIG. 4 is a front view of a fourth embodiment of the display screen with graphical user interface of an incubator.

FIG. 5 is a front view of a fifth embodiment of the display screen with graphical user interface of an incubator.

FIG. 6 is a back view of the display screen with graphical user interface of an incubator.

FIG. 7 is a top view thereof.

FIG. 8 is a bottom view thereof.

FIG. 9 is a right side view thereof; and,

FIG. 10 is a left side view thereof.

The broken lines in FIGS. 1-10 showing the monitor are included for the purpose of illustrating environmental structure and form no part of the claimed design. The broken lines within the monitor in FIGS. 1-5 illustrate graphical features that form no part of the claimed design.

1 Claim, 10 Drawing Sheets
